[57] **CLAIM**

The ornamental design of a magnetic memo board, as shown and described.

DESCRIPTION

FIG. 1 is a front elevational view of a magnetic memo board showing my new design;

FIG. 2 is a rear elevational view thereof;

FIG. 3 is a side elevational view thereof; the opposite side being a mirror image thereof; and,

FIG. 4 is a top view thereof; the bottom view being a mirror image thereof.
